United States Patent Office

Des. 219,075
Patented Oct. 27, 1970

219,075

STAMP PAD OR THE LIKE

Eugene J. Majewski, 121 Elmore St.,
Park Ridge, Ill. 60068

Filed June 16, 1969, Ser. No. 17,716

Term of patent 14 years

Int. Cl. D18—99

U.S. Cl. D64—10

FIG. 1

FIG. 2

FIG. 3

FIG. 4

FIG. 1 is a top plan view of a stamp pad or the like, showing my new design.

FIG. 2 is a side elevational view thereof.

FIG. 3 is a front elevational view thereof.

FIG. 4 is a perspective view thereof.

I claim:

The ornamental design for a stamp pad or the like, as shown.
